UNITED STATES PATENT OFFICE.

JAMES BARLOW, OF TRENTON, NEW JERSEY.

DESIGN FOR A VEGETABLE-DISH.

SPECIFICATION forming part of Design No. 16,310, dated October 6, 1885.

Application filed July 25, 1885. Serial No. 172,682. Term of patent 3½ years.

To all whom it may concern:

Be it known that I, JAMES BARLOW, a citizen of the United States, residing in Trenton, in the county of Mercer and State of New Jersey, have invented and produced a new and original Design for Vegetable-Dishes of China, Porcelain, and Crockery Wares, of which the following is a specification, reference being had to the accompanying photographs, forming part thereof.

Figure 1 is a top or plan view of the lid of the dish, and Fig. 2 is a perspective view of the dish with the lid on, these two views being deemed necessary to fully illustrate my design.

The leading features of my design consist in the rectangular corners, the handles joined to the ends of the dish and the lid by bifurcated ends, the fluting on the upper edge of the dish, and the radial fluting on the middle part of the lid, the scallops on the edge of the lid and the bottom edge of the dish, the claw-feet corners, and the beading on the lower part of the sides or walls of the dish.

A is the lid; B, the radial fluting thereon. C C are the bifurcated handles on the ends of the dish and on the lid.

D and D' are the scallops on the edge of the lid and on the bottom edge of the dish, respectively.

E is the fluting at the top edge of the dish, and G G are the claw-feet corners.

The lid of the dish is oblong and rectangular in outline, being slightly arched from the edges to the middle. The radial fluting B on the middle of the lid is also oblong and rectangular in outline, and from this fluted part

rises the handle C, with bifurcated ends. On the edges of the lid, projecting from below a slight offset, are the scallops D. The body of the dish is oblong and rectangular, the walls being nearly vertical to the plane of the bottom of the dish. From the middle of each end wall projects a bifurcated handle, C C, one of which appears in full view in Fig. 2. On the top edges of the walls of the dish is the fluting E, while at the bottom edge of the dish are the scallops D', and at the bottom corners are the claw-feet G G.

What I claim is—

1. The design for a vegetable-dish of china, porcelain, or crockery ware, oblong and rectangular in form, having handles C C, with bifurcated ends, claw-feet G G, scalloped bottom edge, D', and fluted upper edge, E, having a lid with scalloped edge D, radially-fluted center B, and bifurcated handle C, as shown and described.

2. In a design for a vegetable dish, the design for the lid thereof, said lid being of oblong and rectangular form, and having scalloped edge D, radially-fluted center B, and bifurcated handle C, as shown and described.

3. In a design for a vegetable dish, the design for the dish-body thereof, said dish being of oblong and rectangular form, and having handles C C, with bifurcated ends, claw-feet G G, scalloped bottom D', and fluted upper edge, E, as shown and described.

JAMES BARLOW.
